STOKER CONSTRUCTION

Edwin Archer Turner, New York, N. Y., assignor,
by mesne assignments, to The Standard Stoker
Company, Inc., New York, N. Y., a corporation
of Delaware

Application February 17, 1934, Serial No. 711,642
Renewed April 8, 1938

12 Claims. (Cl. 110—104)

My invention relates to stokers of the type which feed through an opening in an upright wall of a furnace and more particularly to certain improvements in the construction of stokers for installation to existing locomotives in which the backhead of the firebox is provided with a firing opening of conventional form and size.

With the various types of stokers manufactured for installation on locomotives, it has been the experience that those which feed through the firing opening in the backhead of the locomotive possess many attributes of simplicity and economy of operation not found in many of the other types. Hence, the stokers of the general type described have found considerable favor with the railroads. However, there is one deterrent to the widespread installation of such stokers on existing locomotives, and that is the cost of enlarging the firing opening so that the stoker may feed through the lower half thereof while the upper half is used as an inspection or hand firing opening. When the firing opening is enlarged, either a portion of or an entire backhead is replaced by a new structure containing this enlarged opening. This is a costly and a time consuming task, and the expense entailed in making this change must be charged to the ultimate cost of the stoker.

This deterrent is obviated by the present invention which has for its main object the provision of an improved stoker of the class described adapted to feed through the conventional size of firing opening. It follows, of course, that the stoker may be utilized also with the larger openings.

Another and more specific object of this invention is to provide an improved stoker, as contemplated by the main object of the invention, characterized by a compact, simplified and novel construction of the stoker discharge conduit and the associated parts of the distributor apparatus whereby such parts occupy a minimum of space in the firing opening and afford free access into the firebox.

A further object of this invention resides in the provision, in a stoker of the above described character, of a novel relation between the pressure fluid jet head, the distributing table and the stoker discharge conduit; the pressure fluid head being rigidly but detachably secured to the discharge conduit, while the distributing table is interlocked with the conduit by a lug and groove connection permitting quick removal of the table from the firing opening whenever it is necessary

for a workman to enter the firebox or for other reasons.

Other objects and advantages reside in the novel construction of the individual parts and in their relations one with another whereby a stoker is produced which may be installed on existing types of locomotives without changing the backhead or disturbing the accessories mounted thereon.

In the drawings accompanying the specification,

Figure 1 is a longitudinal sectional view of the rearward portion of a locomotive showing the invention in similar section with some portions in elevation and others broken away to illustrate the structure;

Figure 2 is a plan view taken on the line 2—2 of Figure 1;

Figure 3 is a view as seen from the interior of the firebox in Figure 1, looking in the direction 3—3;

Figure 4 is an enlarged sectional view taken on the line 4—4 of Figure 2;

Figure 5 is a view similar to Figure 1 showing one modification of my invention;

Figure 6 is a rear elevational view taken on the line 6—6 of Figure 5;

Figure 7 is an enlarged sectional view similar to Figure 4 of a portion of the modification illustrated in Figure 5;

Figure 8 is a view similar to Figures 1 and 5 showing another modification of the invention;

Figure 9 is an enlarged sectional view similar to Figures 4 and 7 of a portion of the modification illustrated in Figure 8; and

Figure 10 is a view similar to Figure 4 showing another modification of this invention.

Referring now to the preferred form of my invention illustrated in Figures 1 to 4, inclusive, 10 represents a locomotive, 11 the boiler thereof, 12 the hollow backhead including the outer sheet 13 and the inner sheet 14. At a suitable distance above the cab deck 15 and the grates 16 of the firebox 17, the inner and outer sheets are flanged inwardly toward each other to form the conventional firing opening 18. This firing opening 18 is usually elliptical in shape and measures approximately sixteen (16) inches in height and twenty (20) inches in width, thereby affording free entry into the firebox. It is, of course, understood that in some instances these dimensions will vary.

The outer sheet 13 of the boiler is covered by lagging 19 which is usually composed of magnesia and asbestos applied in sections or in plastic

25

30

35

40

45

50

55

form. The lagging 19 prevents the loss of heat in the boiler through radiation. A jacket 20 of planished sheet iron fits over the lagging and forms a protecting cover therefor. It will be observed from Figures 1 and 2 that the lagging 19 and the jacket 20 terminate somewhat short of the outer marginal edge defining the firing opening 18, leaving a portion of the outer sheet 13 adjacent the firing opening uncovered.

10 A fuel feed device for transferring fuel from the tender to the locomotive is shown generally as S and comprises a stoker riser or discharge conduit 21 on the locomotive and the trough conduit 22 leading forwardly from the tender (not shown) and delivering to the discharge conduit 21 at a point below the cab deck 15. A universal joint connection 22a provides for the flexibility necessary between the conduits 21 and 22 when the locomotive and tender are rounding curves or crossing switches and turntables.

15 The construction of the discharge conduit 21 is novel and will now be described in detail. It comprises the casing 23 and the feed tube 32, the former being rigidly secured to the uncovered portion of the outer sheet 13 as by means of studs or bolts 24 passing through the laterally extending flanges 25. The casing 23 includes the upper arcuate wall 26 and the curved side walls 27, the outer marginal edges 28 of which together with 20 the upper edge 32a of the rear wall of the tube 32 define an aperture 29 opposite the firing opening 18. A firedoor 30 is supported from the casing 23 and forms a movable closure for the aperture 29. The firedoor illustrated is of the well known "Franklin butterfly" type having a motor M and a hand lever 31 whereby the firedoor may be operated manually or by power means. It will be observed from Figure 1 that the uppermost edge of the arcuate top wall 26 25 is placed close to the backhead 12 and as a consequence the firedoor operating mechanism does not extend outwardly from the backhead a distance which would interfere with hand firing, inspection of fire conditions or entry into the firebox.

30 As the sidewalls 27 extend downwardly their outer marginal edges which are in the same inclined plane extend outwardly from the backhead a greater distance progressively until at the lowermost point represented by the edge 32a, this point is spaced from the backhead a horizontal distance which is approximately twice the horizontal distance from the uppermost edge of the upper wall 26 to the backhead. It will be observed the stoker feed tube 32 slopes upwardly from beneath the deck 15 at an angle approximating 45 degrees and opens upwardly into the casing 23. The walls of the latter constitute continuations of the tube 32 which is rigidly attached to the casing by means of bolts 33 passing through the flanges 34 and 35 of the casing and the tube, respectively. At its forward end, the tube 32 is secured to the backhead by means of bolts or studs 36 passing through the flange 37, which is similar to the flange 25 of the casing 23 and in alignment therewith. If desired the casing and the tube may be integrally formed but for convenience of manufacture and assembly it is preferred that they should be constructed 35 separately as described to form the conduit 21.

35 The upwardly opening portion of the tube 32 includes side walls 38 which extend a slight distance into the firing opening 18 and curve toward each other to form the bottom or forward wall 39. It will be observed that the central

portion of the bottom wall 39 terminates short of the outer sheet 13 adjacent the firing opening 18, thereby forming a recess 40 included between the side walls 38 for receiving a pressure fluid jet head 41. This jet head 41 is cored to form the high pressure chamber 42 and the low pressure chamber 43 which receive pressure fluid through pipes such as that shown at 44. At its rearward end, the pressure fluid jet head is provided with vertically drilled holes 45 counter-bored as at 46. 10 Studs 47 are screwed into the flanges 48 formed with the bottom or forward wall 39 and the jet head 41 is seated on each flange so that the holes 45 thereof engage the studs 47. These flanges 48 do not extend across the width of the recess 40 but are formed only beneath each counter-bored portion 45. In this manner, the flow of cooling air currents beneath the jet head 41 is not restricted. Nuts 49 are utilized to firmly engage each stud, thereby securely, but detachably, holding the jet member in the recess 40. For convenience of assembly, the rearward end of the jet head 41 and the securing means therefor, lie between the vertical planes passed through the upper and lower extremities of the aperture 29. 20

25 In the preferred embodiment of my invention illustrated in Figures 1 to 4 inclusive, a system of connected screws convey the fuel from the tender to a point adjacent the firing opening. A screw 50 in the trough conduit 22 is flexibly connected to the screw 51 of the riser conduit 21 by a double universal joint 52 and this last named screw 51 conveys the fuel along the bottom wall 39 and thence urges the same over the upper wall 53 of the jet head 41. The upper wall 53 of the jet head has a lower portion 53a which forms an upward continuation of the bottom wall 39, so that the fuel is urged along a smooth surface free of any irregularities, while the upper portion 53b of the jet head curves forwardly from the straight lower portion and is disposed slightly above the lower marginal edge of the firing opening but below the lowermost edge of the aperture in the casing 23. Preferably, the straight portion 53a is a tangent of the curved portion 53b and by this construction, together with the relation existing between the bottom wall 39 and the portion 53a, a free and easy passage for the fuel through the discharge conduit is provided.

30 As coal passes over the jet head 41, it is subjected to a separation of the finer particles from the coarser particles and then falls onto the upper surface 54 of the distributing table 55, from which it is projected to all parts of the firebed, in a manner which is now to be described.

35 Extending forwardly from the high pressure chamber or chambers 42 are the finger-like projections 56 which are spaced apart and radiate from the jet head 41. Each finger-like projection 56 is provided with a passage such as 57 for emitting a blast of pressure fluid over the upper surface 54 of the table 55 and also over the low pressure blasts of pressure fluid issuing from the orifices 58 of the low pressure chamber or chambers 43. Thus, the larger lumps of fuel roll over the projections 56 while the finer particles sift through and fall in front of the low pressure orifices. The low pressure blast will spread the finer particles over the entire firebed, while the higher pressure blasts project the larger lumps 40 forwardly. Of course, some of the larger lumps of fuel will be acted upon by the combined force of the high and low pressure blasts while some of the intermediate lumps of fuel will be acted upon solely by the low pressure blasts. This, 45

together with the curved deflectors 59 which are formed with the table 55, constitutes a very efficient distributing system.

Another desirable result which is gained by the use of the high and the low pressure blasts in this particular instance is that the high pressure blasts of pressure fluid act as a cover over the finer particles of fuel and prevent their being drawn out through the stack by the high drafts. This is especially true when the stoker feeds through the firing opening of conventional form and size, because in these instances, the stoker delivers fuel onto the distributing table at a relatively higher point above the grate level than with stokers of former construction, and hence the fuel as it is projected from the table 55 must pass through the more swiftly moving gas currents and also must traverse a greater distance before falling on the grate. So that the distributing table 55 may be easily renewed or removed for the purpose of affording more space when entry into the firebox is made, the curving side walls 38 of the discharge conduit are arranged to detachably support this member in a novel and advantageous manner. For this purpose, each side wall 38 at the forward end thereof is provided with an upwardly opening hook member 60 while the distributing table 55 is provided with the upwardly extending flanges 61 which form extensions of the curving side walls and have formed therein the downwardly opening hook members 62 for engaging the hook members 60. Since the detachable connection means between the table 55 and the discharge conduit is a substantial distance above the table 55 and removed from the damaging effects of the heat in the firebox, removal of the table will be facilitated and its life prolonged.

Whenever access into the firebox is to be made, pressure fluid is admitted into the chamber 63 at the rear wall 64 of the discharge conduit and emitted through the forwardly directed passages 65, thereby removing any coal which remains in the open mouth of this conduit. This remaining coal can also be pushed forwardly by manual means, thereby obviating the use of the blast chamber 63. The firedoor 30 is then opened preferably by hand and if the table 55 extends into the firebox a distance which makes entry thereto inconvenient, it may be unhooked and removed. Should it be necessary to remove the jet head 41, a socket wrench may be fitted into the counter-bored portions 46 and the nut members 49 removed. The removal of the nut members 49 will not cause the jet head to fall forwardly into the firebox because the studs 47 effectively engage the drilled holes 45. It will be observed from Figure 1 that the jet head 41 when in position in the firing opening is substantially below the lower marginal edge of the aperture 29 and is constructed so that it curves forwardly and upwardly to a point in the firing opening and then slopes downwardly. By such construction of the jet head, the upper surface thereof does not form a tunnel with the upper sheets of the firing opening, thereby making possible free access into the firebox. In certain instances, the upper chambers 42 will not be necessary and only the lower chamber 10, will be necessary. This construction is shown in Figure 10 and it will be apparent that by the use of only the lower chamber or chambers 10, a greater effective firing opening will be available for entry into the firebox.

In Figures 5, 6 and 7, the fuel feed tube com-

prising the discharge conduit is in the form of a forwardly and upwardly curving conduit member 71, while the trough screw 72 terminates somewhat short of the forward wall 73 thereof and forces the fuel forwardly and upwardly over the jet head 41 and onto the distributing table 55. Otherwise, the construction of this modification is similar to the preferred form illustrated in Figures 1 to 4, inclusive.

Another modification of the invention is illustrated in Figures 8 and 9, and in this construction a fuel feed tube 74 extends upwardly along the vertical medial plane of the firebox and substantially parallel thereto. This tube 74 terminates below the level of the firing opening 18 and feeds upwardly into the lower extension 75 of the casing 76 which embraces the firing opening. A casing of this form can also be used in the first two forms of my invention. A trough screw 77 in the conduit 78 feeds coal into the rearward extension 79 of the tube 74. This tube houses a screw 80 which is driven from its lower end by means of gearing 81 in the gear case 82. Since the casing 76 is provided with the integral lower extension 75, the recess 83 for the jet head 41 is formed in the lower extension of the casing instead of in the feed tube. The upper end of the screw 80 terminates below the lowermost edge of the aperture 29 so that it does not form an obstruction to hand firing or entry into the firebox.

From the foregoing description and illustrations of my invention it will be realized by those familiar with the problems encountered in the practical construction of locomotive stokers that many of these problems which exist are solved by the various novel features embodied herein. It will also be understood that the features of one type of stoker can also be used with stokers of other types, as demonstrated herein. I define my invention in the appended claims.

I claim:

1. In combination with a locomotive firebox having a firing opening in the backwall thereof, a fuel feed device delivering into said opening including a casing connected to said backwall and having top and side walls partially surrounding the firing opening, the rear marginal edges of said top and side walls lying in a common inclined plane and being spaced from said backwall to define an aperture opposite said firing opening, the lowermost edge of said aperture being spaced from said backwall a horizontal distance which is approximately twice the horizontal distance from the uppermost edge of said aperture to said backwall, a movable closure carried by said casing for such aperture, a fuel feed tube extending upwardly toward and delivering into said casing, said tube and casing constituting a stoker discharge conduit, said conduit having a forward wall terminating adjacent the lower marginal edge of said firing opening and short of said backwall, and side walls extending beyond the forward wall to form a recess adjacent the lower portion of said firing opening, a pressure fluid jet head received in the recess formed between the aforesaid forward and side walls of said conduit, and a fuel distributing table forward of said jet head, said fuel distributing table detachably engaging said conduit above said jet head.

2. In combination with a locomotive firebox having a firing opening in the backwall thereof, a fuel feed device delivering into said opening including a casing connected to said backwall

and having top and side walls partially surrounding the firing opening, the rear marginal edges of said top and side walls lying in a common inclined plane and being spaced from said backwall to define an aperture opposite said firing opening, the lowermost edge of said aperture being spaced from said backwall a horizontal distance which is approximately twice the horizontal distance from the uppermost edge of said aperture to said backwall, a movable closure carried by said casing for such aperture, a fuel feed tube extending upwardly toward said casing at an angle approximately 45 degrees from the horizontal and delivering into said casing, said tube and casing constituting a stoker discharge conduit, said tube having a forward wall terminating adjacent the lower marginal edge of said firing opening and short of said backwall, and side walls extending forwardly beyond said forward wall to form a recess adjacent the lower portion of said firing opening, said side walls extending upwardly above the lower marginal edge of said firing opening to form continuations of the side walls of said casing, a pressure fluid jet head received in the recess formed between the aforesaid forward and side walls of said tube, a fuel distributing table forward of said jet head detachably engaging the side walls of said tube above said jet head, and a conveyor screw in said fuel feed tube, the forward end of said conveyor screw terminating adjacent the recessed portion of the tube and below the lowermost edge of the aperture in said casing.

3. In combination with a locomotive firebox, having a firing opening in the backwall thereof, a fuel feed device delivering into said opening including a casing connected to said backwall and having top and side walls partially surrounding the firing opening, the rear marginal edges of said top and side walls lying in a common inclined plane and being spaced from said backwall to define an aperture opposite said firing opening, the lowermost edge of said aperture being spaced from said backwall a horizontal distance which is approximately twice the horizontal distance from the uppermost edge of said aperture to said backwall, a movable closure for such aperture, a conduit member curving forwardly and upwardly toward said casing and delivering thereto above the lower marginal edge of said firing opening, said conduit member and casing constituting a stoker discharge conduit, said conduit member having a forward wall terminating adjacent the lower marginal edge of said firing opening and short of said backwall, and side walls extending forwardly beyond said wall to form a recess adjacent the lower portion of said firing opening, said side walls extending upwardly above the lower marginal edge of said firing opening to form continuations of the side walls of said casing, a pressure fluid jet head received in the recess between the aforesaid forward and side walls of said conduit member, and a fuel distributing table engaging the side walls of said conduit member above said jet head.

4. In combination with a locomotive firebox having a firing opening in the backwall thereof, a fuel feed device delivering into said opening including a casing connected to said backwall and having top and side walls partially surrounding the firing opening, the rear marginal edges of said top and side walls lying in a common plane and being spaced from said backwall to define an aperture opposite said firing opening, the lowermost edge of said aperture being spaced

from said backwall a horizontal distance which is approximately twice the horizontal distance from the uppermost edge of said aperture to said backwall, a movable closure for such aperture, said casing having a lower extension terminating below the lower marginal edge of said firing opening, said extension having a forward wall terminating adjacent the lower marginal edge of said firing opening and short of said backwall, the side walls of said casing extending forwardly beyond said forward wall, a pressure fluid jet head received in the recess formed between the aforesaid forward and side walls of said casing, a fuel distributing table forward of said jet, said fuel distributing table detachably engaging the side walls of said casing above said jet head, a fuel feed tube connected to the lower extension of said casing and extending along said backwall substantially parallel thereto, and a conveyor screw in said tube, the upper end of said conveyor screw terminating below the lowermost edge of the aperture in said casing.

5. In a locomotive having a firebox with a firing opening in the backwall thereof, the combination including a casing secured to said backwall, said casing having a top wall extending rearwardly from the upper marginal edge of said firing opening and side walls extending rearwardly from corresponding side marginal edges of such opening, a fuel feed tube communicating with said casing, said fuel feed tube including a forward wall terminating adjacent the lower marginal edge of said firing opening and a rear wall spaced above the upper edge of the forward wall, the rear marginal edges of the top and side walls of said casing lying in a common plane and forming with the upper edge of the feed tube rear wall a forwardly and upwardly inclined aperture opposite said firing opening, the forward wall of said feed tube terminating intermediate the transverse vertical planes passed through the uppermost and lowermost marginal edges of said aperture, the transverse vertical plane passed through the uppermost limit of said aperture passing closely adjacent the rearward lower marginal edge of said firing opening, the side walls of said tube forming continuations of the side walls of said casing and extending beyond said forward wall to form a recess, a pressure jet head seated in said recess forming a continuation of the forward wall of said tube, and means for detachably securing said jet head to said fuel feed tube, said means being disposed between the aforesaid vertical planes.

6. In a locomotive having a firebox with a firing opening in the backwall thereof, the combination including a casing secured to said backwall, said casing having a top wall extending rearwardly from the upper marginal edge of said firing opening and side walls extending rearwardly from corresponding side marginal edges of such opening, a fuel feed tube communicating with said firing opening and delivering into said casing, said fuel feed tube including a forward wall terminating adjacent the lower marginal edge of said firing opening and a rear wall spaced above the upper edge of the forward wall, the rear marginal edges of the top and side walls of said casing lying in a common plane and forming with the upper edge of the feed tube rear wall a forwardly and upwardly inclined aperture opposite said firing opening, the forward wall of said feed tube terminating intermediate the transverse vertical planes passed through the uppermost and lowermost marginal edges of said aperture, the

transverse vertical plane passed through the uppermost limit of said aperture passing closely adjacent the rearward lower marginal edge of said firing opening, the side walls of said tube forming continuations of the side walls of said casing and extending beyond said forward wall to form a recess, a pressure jet head seated in said recess forming a continuation of the forward wall of said tube, and means disposed between the aforesaid vertical planes for detachably securing said jet head to said fuel feed tube, said means including a threaded projection carried by said tube and engaging said jet head, and a threaded member engaging said threaded projection.

7. In a locomotive having a firebox with a firing opening in the backwall thereof, the combination including a casing secured to said backwall, said casing having a top wall extending rearwardly from the upper marginal edge of said firing opening and side walls extending rearwardly from corresponding side marginal edges of such opening, a fuel feed tube communicating with said firing opening and delivering into said casing, said fuel feed tube including a forward wall terminating adjacent the lower marginal edge of said firing opening and a rear wall spaced above the upper edge of the forward wall, the rear marginal edges of the top and side walls of said casing lying in a common plane and forming with the upper edge of the feed tube rear wall a forwardly and upwardly inclined aperture opposite said firing opening, the forward wall of said feed tube terminating intermediate the transverse vertical planes passed through the uppermost and lowermost marginal edges of said aperture, the transverse vertical plane passed through the uppermost limit of said aperture passing closely adjacent the rearward lowermost edge of said firing opening, the side walls of said tube forming continuations of the side walls of said casing and extending beyond said forward wall to form a recess, a pressure jet head seated in said recess forming a continuation of the forward wall of said tube, and means disposed between the aforesaid vertical planes for detachably securing said jet head to said fuel feed tube, said means including a threaded projection carried by the forward wall of said tube closely adjacent said recess, such threaded projection freely engaging said jet head, and a threaded member engaging said threaded projection.

8. In a locomotive having a firebox with a firing opening in the backwall thereof, the combination including a casing secured to said backwall, said casing having a top wall extending rearwardly from the upper marginal edge of said firing opening and side walls extending rearwardly from corresponding side marginal edges of such opening, the rear marginal edges of said top and side walls lying in a common inclined plane spaced from said backwall, a fuel feed tube communicating with said firing opening and delivering into said casing, said fuel feed tube including a forward wall terminating adjacent the lower marginal edge of said firing opening and a rear wall spaced above the upper edge of the forward wall, the rear marginal edges of the top and side walls of said casing lying in a common plane and forming with the upper edge of the feed tube rear wall a forwardly and upwardly inclined aperture opposite said firing opening, the forward wall of said feed tube terminating intermediate the vertical planes passed through the uppermost and lowermost marginal edges of

said aperture, the transverse vertical plane passed through the uppermost limit of said aperture passing closely adjacent the rearward lower marginal edge of said firing opening, the side walls of said tube forming continuations of the side walls of said casing and extending beyond said forward wall to form a recess, a pressure jet head seated in said recess forming a continuation of the forward wall of said tube, and vertically disposed fastening members detachably securing said jet head to said fuel feed tube, said fastening means being disposed between the aforesaid vertical planes.

9. In combination with a firebox having a wall with a firing opening therein, a stoker discharge conduit communicating with said firing opening, a pressure fluid jet head secured to said conduit, a distributing table extending forward of said jet head and having a fuel supporting upper surface, a flange at the rear of each side of said table extending above the fuel supporting surface thereof rearwardly to a point beyond the lateral limits of said surface, the rearward end of each flange being provided with a hook member opening downwardly, and means providing an upwardly opening hook member at each side of said conduit, the downwardly opening hook members of said distributing table being adapted to engage the respective upwardly opening hook members adjacent the sides of said conduit and cooperating to support said distributing table in a predetermined relation with said jet head, said hook members being engageable with and disengageable from each other upon downward and upward straight line movement, respectively, of said distributing table.

10. As an article of manufacture, a distributing table having a fuel supporting surface disposed substantially in a horizontal plane when said distributing table is in its operative position, and a flange extending outwardly from each side of said table and at one end thereof to a point above the fuel supporting surface and beyond the lateral limits thereof, each flange being provided with a downwardly opening hook member in a plane above the fuel supporting surface, said flanges and fuel supporting surface defining an upwardly opening channel at one end of said table for constraining fuel therein.

11. In combination with a firebox having a wall with a firing opening therein, a stoker discharge conduit provided with a mouth portion communicating with said firing opening, a pressure fluid jet head mounted at the bottom of said mouth portion, a distributing table forward of said jet head and having a fuel supporting upper surface, a flange at each side of said table extending upwardly and rearwardly above the fuel supporting surface thereof, the rearward end of each flange being provided with a hook member opening downwardly, and means providing an upwardly opening hook member at each side of said conduit, the downwardly opening hook members of said distributing tables being adapted to engage the respective upwardly opening hook members adjacent the sides of said conduit and cooperating to support said distributing table in a predetermined relation with said jet head, said jet head having a series of jet openings for the emission of pressure fluid across said fuel supporting surface, said hook members being engageable with and disengageable from each other upon movement in a downward and upward direction, respectively, of said distributing table.

12. As an article of manufacture, a distributing

table for a stoker having a fuel supporting surface disposed substantially in a horizontal plane when said distributing table is in its operative position, and a flange extending upwardly from each side of said table and at one end thereof defining with said fuel supporting surface an upwardly opening channel at the said end of

the table for constraining fuel therein, said flanges also extending rearwardly beyond the limit of the fuel supporting surface of the said end of said table, each flange being provided with a downwardly opening hook member in a plane above the fuel supporting surface.

E. ARCHER TURNER.
